PODIATRIST CHAIR

Hyman J. Rose, Swampscott, Mass., assignor to Contour
Chair-Lounge Co., Inc., St. Louis, Mo., a corporation
of Missouri

Filed Sept. 3, 1963, Ser. No. 76,454

Term of patent 14 years

(Cl. D15—11)

FIGURE 1 is a side elevational view of a podiatrist chair showing my new design;

FIGURE 2 is a side elevational view thereof, showing the other side;

FIGURE 3 is a top plan view thereof;

FIGURE 4 is a rear elevational view thereof;

FIGURE 5 is a front elevational view thereof;

FIGURE 6 is an isometric view thereof, the near arm rest being in lowered position; and

FIGURE 7 is an isometric view thereof, the arms being in lowered positions.

I claim:

The ornamental design for a podiatrist chair, as shown.
